CLAIM

The ornamental design for a water bottle organizer, as shown and described.

DESCRIPTION

FIG. 1 is a front elevational view of a water bottle organizer showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is an enlarged view of the encircled portion '9' in FIG. 1;

FIG. 10 is an enlarged view of the encircled portion '10' in FIG. 2;

FIG. 11 is an enlarged view of the encircled portion '11' in FIG. 5;

FIG. 12 is an enlarged view of the encircled portion '12' in FIG. 7; and,

FIG. 13 is an enlarged view of the encircled portion '13' in FIG. 8.

The dashed broken lines shown in FIGS. 1-13 are for the purpose of illustrating portions of the article and form no part of the claimed design. The dotted broken lines in FIGS. 1, 2, 5, and 7-13 represent unclaimed boundary lines and form no part of the claimed design.

The dot-dot-dash broken line circles in FIGS. 1-2, 5, and 7-13 depict the limits of the enlarged views and form no part of the claimed design.

1 Claim, 13 Drawing Sheets
